COMBINATION AIR INTAKE AND VECTOR CONTROL FOR POULTRY BUILDINGS

Donald L. De Myer, % Cycle Systems, Inc., 9290 Belding
Road, Rockford, Mich. 49341

Filed June 20, 1974, Ser. No. 481,391

Term of patent 14 years

Int. Cl. D23—04; D25—02

U.S. Cl. D23—153

FIG. 1 is an end and top isometric view of a combination air intake and vector control for poultry buildings embodying my new design as viewed from the inlet face.

FIG. 2 is another end and top isometric view of the combination air intake and vector control for poultry buildings shown in FIG. 1, viewed from the discharge face.

FIG. 3 is an end elevation of the combination air intake and vector control for poultry buildings shown in FIG. 1 and FIG. 2.

FIG. 4 is an elevational view thereof, with the combination air intake and vector control for poultry buildings mounted in a portion of such building; all broken lines are for illustrative purposes only and do not form a part of the claimed article.

The screen pattern which is partially visible in FIGS. 1 and 2 is understood to repeat uniformly across the length and width of the area.

I claim:

The ornamental design for a combination air intake and vector control for poultry buildings, as shown and described.
